Attorney

UNITED STATES PATENT OFFICE.

JOHN P. BENJAMIN, OF EAST PROVIDENCE, RHODE ISLAND.

DESIGN FOR A FOUNTAIN PEN.

Application filed February 9, 1924. Serial No. 8,585. Term of patent 14 years.

To all whom it may concern:

Be it known that I, JOHN P. BENJAMIN, a citizen of the United States, residing at East Providence, in the county of Providence and State of Rhode Island, have invented new, original, and ornamental Design for a Fountain Pen, of which the following is a specification, reference being had to the accompanying drawings, forming part thereof.

I claim:

The ornamental design for a fountain pen, as shown.

In testimony whereof I have signed my name to this specification in the presence of two subscribing witnesses.

JOHN P. BENJAMIN.

Witnesses:

S. N. McCCLARENCE,
J. A. MILLER.
